UNITED STATES PATENT OFFICE.

PATRICK JOSEPH DEVER, OF FREELAND, PENNSYLVANIA.

SWITCH.

Application filed July 3, 1924. Serial No. 724,063.

To all whom it may concern:

Be it known that I, PATRICK J. DEVER, a citizen of the United States, residing at Freeland, in the county of Luzerne and State of Pennsylvania, have invented a new and useful Switch, of which the following is a specification.

This invention relates to a switch mechanism especially designed for controlling the electric circuits to the headlights of a motor vehicle.

The primary object of the invention is to provide a switch of this character which will be automatically controlled by the turning 15 of the front wheels of the motor vehicle so that the light rays projected from the headlights will be directed in the path of travel of the motor vehicle to properly illuminate the road surface over which the vehicle is 20 moving.

Another important object of the invention is to provide a water-proof switch, and one wherein the contact members of the switch will be completely housed and guarded 25 against foreign matter collecting on the elements of the switch to render the same inoperative.

With the foregoing and other objects in view which will appear as the description 30 proceeds, the invention resides in the combination and arrangement of parts and in the details of construction hereinafter described and claimed, it being understood that changes in the precise embodiment of the invention herein disclosed, may be made within 35 the scope of what is claimed, without departing from the spirit of the invention.

Referring to the drawing:

Figure 1 is a fragmental plan view 40 closing a switch constructed in accordance with the invention as supported on the spindle arm connecting rod of a motor vehicle.

Figure 2 is a sectional view taken on line 2-2 of Figure 3.

Figure 3 is a sectional view taken on line 45 3-3 of Figure 2.

Figure 4 is a sectional view taken on line 4-4 of Figure 3.

Figure 5 is a longitudinal sectional view 50 taken on line 5-5 of Figure 2.

Referring to the drawing in detail, the reference character 5 designates the usual front axle of a motor vehicle which is forked at its ends in the usual manner to provide 55 bearings for the usual spindles or stub shafts 6 on which the front wheels 7 are mounted.

Extending rearwardly from the spindles 6 are the spindle arms 8 which are connected by the usual spindle arm connecting rod 9 to which rod the switch, forming the subject 60 matter of the invention, is supported. The switch includes a main casing 10 formed with upstanding end portions 11 and 12 respectively, in which the insulating block 13 is positioned. Forming a part of the casing 65 is a section 14 formed with right angled end portions 15 that are held in such relation with the end members 11 and 12 of the main casing 10 to house the insulating block 16, that is disposed adjacent to the insulating 70 block 13.

The reference character 17 designates the side walls of the casing 10 between which the section 14 is disposed and as shown, portions of the walls 17 extend outwardly 75 beyond the section 14 providing tongues 18, for purposes to be hereinafter more fully described.

Securing clips 19 embrace portions of the section 14 and casing 10 and are formed with 80 suitable openings to receive the bolts 20 by means of which the entire device is secured to the rod 9. The insulating block 13 is cut away at 21 to expose the wires 22 that are embedded in the insulating block 13 and 85 constitute circuit wires to a lamp in a head-light of a motor vehicle.

The insulating block 16 is also cut away at 23 and provides a housing for the spring 90 arms 24 that have one end thereof secured within the insulating block 16 by means of the pin 25, the opposite end of the arm extending beyond one end of the casing as at 26, where the same supports a threaded tubular member 27 secured to one surface of 95 the arm 26.

Fitted in the member 27 is a threaded member 28 designed to move within the member 27 so that the same may be adjusted with respect thereto, one end of the member 100 28 being flattened as at 29 where the same may pass into the slot 30 of the socket member 31, carried by the curved spring arm 32 which in turn engages the cam 33 formed on the spindle 8.

Associated with the wires 22, are wires 34 that extend into the insulating block 13 and are exposed or freed of their insulating material within the cut out portions of the insulating blocks. A spring arm 35 is also secured within the insulating block 16 and extends from the casing where it supports a 110

member 28 to be engaged by the cam 36 which is disposed in a direction opposite to the cam 33 so that upon movement of the spindle arm 8 in one direction to cause the steering of the vehicle, one cam will operate to move a particular spring arm, completing the circuit to a lamp arranged within and adjacent to the usual lamp of a headlight, the auxiliary lamp being disposed at an angle so that the light rays projected therefrom will be projected at an angle illuminating the road surface. Contact members 37 are supported by the arms 24 and insulated therefrom through the medium of the insulating blocks 38, the contact members 37 being of construction so that when they are moved into operation, they will bridge the wires of the circuit associated therewith to complete the circuit therethrough and cause the lighting of the lamps in the circuit, and which are not shown.

Due to the offset relation on the cams 33 and 36, it will be seen that when the spindle arms 8 are moved in one direction, the circuit to one of the lamps will be completed to light the lamp while with a movement of the spindle in the opposite direction, the opposite circuit will be completed to illuminate the auxiliary lamp at the opposite side of the vehicle.

I claim:

1. In combination with a spindle arm having oppositely disposed cams, pairs of wires providing lighting circuits, arms carrying contact members adapted to bridge the wires of the respective pairs of wires to complete circuits therethrough, said arms having tubular members adjacent to their outer ends, threaded members movable through the tubular members, spring arms contacting with the cams and engaged by the threaded members to adjust the arms with respect to the cams, and said cams adapted to operate to move the arms to move the contact members to their active positions.

2. In a device of the character described, a housing, spaced wires positioned within the housing, a spring arm mounted within the housing, one end of the spring arm being secured against movement, said housing having an opening through which the spring arm extends, a contact member carried by the central portion of the spring arm, and means engaging the spring arm to cause the spring arm to bend inwardly from one side of the opening.

In testimony that I claim the foregoing as my own, I have hereto affixed my signature.

PATRICK JOSEPH DEVER.
